(57) **CLAIM**

The ornamental design for a charging base, as shown and described.

DESCRIPTION

FIG. 1 is a perspective view of our new charging base; FIG. 2 is a top view of our new charging base of FIG. 1; FIG. 3 is a side view of our new charging base of FIG. 1, the opposite side view being a mirror image thereof; FIG. 4 is another side view of our new charging base of FIG. 1; FIG. 5 is a side view of our new charging base, opposite that of FIG. 4; and, FIG. 6 is a bottom view of our new charging base. The broken lines are shown for the purpose of illustrating portions of the article that form no part of the claimed design.
